UNITED STATES PATENT OFFICE.

CHARLES D. McDONALD, OF CHICAGO, ILLINOIS, ASSIGNOR TO McDONALD MACHINE CO., OF CHICAGO, ILLINOIS, A CORPORATION OF ILLINOIS.

AUTOMATIC PRESS-STOPPING MECHANISM.

Application filed February 11, 1927. Serial No. 167,412.

This invention relates to automatic press stopping mechanism and its principal object is to provide improved, pneumatically operated mechanism for holding the hand lever of the starting and stopping mechanism of the press in operative position and for automatically releasing said hand lever and thereby stopping the press in case an abnormal condition arises in the feed way of the press, or some other vulnerable place therein. This invention has reference more particularly to automatic die presses, in which strips of material are inserted, one at a time, from a stack of strips into a feed way and therein fed, in a step by step manner, to the dies of the press, where the strips are operated upon, either by blanking out pieces therefrom, or otherwise as is well understood. Occasionally more than one strip of material is accidentally inserted into the feed way, in which case it becomes necessary to stop the press and extract the superfluous strip, and one of the objects of the present invention is to provide improved pneumatic means for stopping the press in case of such an emergency. Sometimes a strip of material becomes buckled in the feed way and it becomes necessary to stop the press and extract the jammed material, and one of the objects of the invention is to provide improved pneumatic means whereby the press is stopped in case a strip becomes jammed in the feed way.

With these and other objects and advantages in view, this invention consists in automatic press stopping mechanism, embodying a pneumatically operated member for holding in position the hand lever of the press starting and stopping mechanism, and means, which are actuated when an abnormal condition arises in the feed way, for admitting air to said pneumatically operated member, whereby the hand lever is released therefrom and permitted to fall, thereby releasing the clutch and applying the brake. The invention further consists in a vacuum head having a suction end arranged to contact with the hand lever of the press starting and stopping mechanism, whereby said lever is thereby held in operative position, in combination with means for releasing the vacuum in the vacuum head, said means being controlled from the feed way of the press. The invention further consists in a vacuum head having a suction end arranged to con-

tact with the hand lever of the press starting and stopping mechanism whereby said lever is held in operative position and means for releasing the vacuum in said vacuum head, which means are controlled by the 60 number of strips which enter the feed way at one time, or an abnormal condition of a feed strip after the strip has been inserted into the feed way. The invention further consists in the several novel features of construction, arrangement and combination of parts hereinafter fully set forth and claimed. 65

The invention is clearly illustrated in the drawings accompanying this specification, in which:

Fig. 1 is a side elevation of an automatic die press partly broken away and stripped of its press mechanism and showing a simple embodiment of my present invention applied to the hand lever of the starting and stopping mechanism; Fig. 2 is a detail cross section taken through the feed way of the press, the line of section being indicated at 2-2 in Fig. 3 looking in the direction of the arrows; Fig. 3 is a view of the feed table and feed mechanism looking in the direction of the arrow 3 in Figs. 1 and 2; Fig. 4 is a detail rear elevation of a fragment of the strip feeding mechanism; Fig. 5 is a detail view, partly in rear elevation and partly in section, through certain connecting elements of said strip feeding mechanism; Fig. 6 is a detail sectional view of the vacuum head which holds the hand lever in operative position, and Fig. 7 is a side elevation of a 70 slightly modified form of the invention.

Referring to said drawings, which illustrate a simple embodiment of the present invention applied to an automatic die press of conventional form, the die press body is 75 seen at 10, and said body supports the various mechanism of the die press. A press of the type illustrated is more fully shown and described in my prior Patents No. 1,252,278, dated January 1, 1918, and No. 1,529,031, dated March 10, 1925, to which reference is herein made. As is well understood presses of this type are equipped with clutch mechanism, whereby a continuously rotating drive pulley may be connected to and disconnected from the crank shaft which operates the ram of the press, and brake mechanism for applying a brake to said crank shaft whenever the clutch is disconnected. As in my prior 80 patents above referred to, the clutch and 85

100

105

110

brake mechanism is controlled from a hand lever 11 fulcrumed upon the press body at 12 and connected to the clutch and brake mechanism by a link 14, an operating strut 13 and links 15, 16 as is well understood. These parts are so proportioned and arranged that when the hand lever 11 is in its upper, or starting position wherein the press operates, the center line between the ends of the link 14 had not passed the fulcrum 12 of the hand lever 11, whereby whenever said hand lever is released from its operative position, as shown in Fig. 1, it may fall by gravity, thereby actuating the clutch and brake mechanism to disconnect the clutch and apply the brake.

At the side of the press, opposite the one seen in Fig. 1, is the feed table 17 of the press. Said feed table has a feed way 18, 20 in its upper side through which the strips of material *a*, are fed to the dies. The feed way 18, is located between the top member 19 of the table and a bar or plate 20 (see Figs. 2 and 3) and finger bar mechanism 21 is mounted in a guide way in the feed table, and has fingers 22 which engage the rear end of the strip of material *a*, and feed the same towards the dies (not shown) in a step by step fashion, as is well understood. 25 The finger bar mechanism is reciprocated by link or connecting rod mechanism, here shown as comprising a link or connecting rod 23, connected to a bell crank lever 24 fulcrumed on a member 25 of the press body 30 and connected to an operating strut 26, which is actuated by the press mechanism as usual and operates to reciprocate the link or connecting rod 23. The connecting rod 23 is connected to the finger bar mechanism 21, 35 by a block 27 secured to the finger bar mechanism and having a pin or stud 28, which engages with the link or connecting rod 23 and is releasably held therein, so that in case a jam occurs in the feed way and movement 40 of the finger bar mechanism is thereby arrested, the connecting rod may continue its movement for an instant, the disconnection between the connecting pin 28 and the connecting rod 23 resulting in the immediate 45 stopping of the press as will be hereinafter explained. The connecting rod has an elongated slot 29 in which the connecting pin 28 may play, and said connecting pin is operatively held at one end of the slot by a 50 spring pressed dog 30 contained in a boss 31 formed on the connecting rod 23 and engaging the side of the connecting pin. The arrangement of these parts is such that said spring pressed dog effectively connects the 55 finger bar mechanism and with the connecting rod, but in case the finger bar meets with an obstruction, the connecting pin 28 thereupon depresses the dog 30 and escapes from the end of the slot, thus permitting the 60 connecting rod to continue its onward move- 65

ment. The connection between the finger bar mechanism and connecting rod is further illustrated and described in my pending application, Serial No. 82,395, filed January 20, 1926.

Secured upon the side of the press body adjacent the hand lever 11, is a vacuum head 32, which contains an air passage 33, that leads from its suction end to the end of a vacuum pipe 34. The vacuum pipe 34 70 leads to a suitable source of vacuum supply and in case the press is provided with a vacuum pump it may lead thereto, otherwise it may lead to a vacuum tank 35 connected with a suitable vacuum pump (not shown). 75 When an independently operated vacuum pump and vacuum tank are used the main vacuum line 36 from the vacuum tank, may lead to the strip lifters, with which presses of this type are equipped, and said pipe may 80 lead any of the other pneumatically operated devices of the press. The suction end of the vacuum head is provided with a resilient suction cup or suction pad 37, which is arranged to contact with a disc like part 38 85 on the hand lever whereby when a partial vacuum is created in said suction head the hand lever will be held against its suction end until the vacuum is released in the vacuum head or the hand lever is forcibly disconnected therefrom. In the conduit or air 90 passage 33 is a spring pressed valve 39, which is adapted to seat upon a valve seat 40 and thereby close the passage through 95 said conduit 33 and said valve 39 is mounted 100 upon a valve stem 41, which may protrude from the suction end of the vacuum head. The part 38 of the hand lever engages with 105 said valve stem 41 whenever the hand lever is raised to its starting or operative position whereby the valve 39 is unseated and the 110 passage from the vacuum pipe 34 to the suction end is opened. When the hand lever is released from the vacuum head, the valve 39 closes the passage through the vacuum 115 head and prevents any leakage of air at 120 this point. It will be observed that so long as a vacuum extends to the suction end of the vacuum head, the hand lever will be effectively held in its starting or operative 125 position, but that in case the vacuum in said suction end of the head is released, the hand lever will be permitted to fall and thereby 130 actuate the clutch and brake mechanism and stop the press. Leading away from the conduit or air passage 33 is a vent tube 42, which has branches connected with trip mechanism, which is set in operation whenever an abnormal condition arises in the feed way 18.

Referring now to Figs. 3, 4, and 5, an air valve 43 will be seen, which is secured upon the connecting rod 23. In its present form, a clamp member 44, secured upon the boss 31 of the connecting rod, is provided 130

for supporting the air valve 43. Said air valve connects with the vent tube 42 through a flexible vent tube 42^a. The air valve 43 is normally closed to the outer atmosphere, but when it is opened thereto, air is admitted to the branch vent tube 42^a, vent tube 42 and the conduit 33 of the suction head, whereupon the vacuum in said conduit is released, and the lever is released from the suction head, falls by gravity and operates the clutch and brake mechanism to stop the press. A trigger 45 is employed for actuating the valve stem 46 of the valve 43 to open the passage through said valve, and said trigger is fulcrumed at 47 upon the clamp member 44 and has a finger 48, which is held in contact with the connecting pin 28 of the link or connecting rod mechanism. A coiled spring 49 secured to the other arm 45^a of the trigger 45 and to the clamp member 44 acts to hold the finger 48 of the trigger 45, in contact with the coupling pin 28. The trigger is shown as formed with a knob or projection 50 which engages with the valve stem 46 in position to depress said valve stem whenever the finger 48 of the trigger is disengaged from the connecting pin 28. As has been explained the connecting pin is releasably held at one end of the slot by the spring pressed dog 30 and remains in such position so long as the condition in the feed way remains normal. In case of a jam therein, however, the finger bar mechanism is arrested and the connecting pin is therefore moved out of the end of the slot upon the continued onward movement of the connecting rod and consequently moves away from the finger 48 of the trigger thereby permitting the spring 49 to draw down the end of the trigger connected therewith and thereby depress valve 46, opening the valve to the outer atmosphere and admitting air to the vacuum head through the vent tube 42 and its branch 42^a whereupon the vacuum in the vacuum head is released and the hand lever falls, and operates the clutch and brake mechanism to stop the press.

The trip device, which is operated by a superfluous number of strips in the feed way is shown in Figs. 2 and 3 and comprises a trip pin 51 slidably mounted in a guiding sleeve 52, which is formed with a part 53 that is bolted or otherwise secured to one of the brackets 54, which carries the strip lifting and inserting mechanism of the press. Said part 53 has a bracket arm 55 extending therefrom, upon which is secured an air valve 56 that is connected to the main vent tube 42 by a branch vent tube 42^b. The trip pin 51 engages with a throw amplifying lever 57 fulcrumed upon the bracket arm 55, and the long arm of said lever 57 engages with the valve stem 58 of the air valve 56.

As a preference an adjustment screw 59 is threadedly secured in the lever 57 and

contacts with the end of the trip pin 51 and furnishes adjustment means for affording a closer adjustment between the lever 57 and trip pin 51. The extent of movement of the long arm of the lever 57, which engages with the valve stem 58 is considerably greater than the extent of movement of that part of the lever which is engaged by the trip pin 51, whereby a slight movement such as is caused by more than one thickness of material under the trip pin will cause a relatively long movement of the outer end of the lever 57, the extent of such movement being sufficient to open the air valve 56.

In the operation of the automatic press stopping mechanism above described, the hand lever 11 is manually raised into contact with the suction end of the vacuum head 32 as seen in Fig. 4, thereby throwing the clutch and brake mechanism into the position wherein the press is started. During normal conditions in the feed way 18, the press continues to run, but in case more than one strip of material is inserted into the feed way 18, the trip pin 51 is thereby raised, the air valve 56 opened, air admitted to the vacuum head 32 through the vent tube 42, the vacuum in said vacuum head is released and the hand lever 11 falls, thereby actuating the clutch and brake mechanism to stop the press. In case a jam occurs in the feed way and the finger bar mechanism is thereby stopped, the connecting pin 28 is drawn out of engagement with the trigger finger 48 as the connecting rod continues its onward movement, and said trigger, being released by the connecting rod, it is drawn down by the spring 49 thereby opening the air valve 43 and admitting air to the vacuum head 32 through the vent tube 42, and the vacuum in the vacuum head is released as before with the same result as before.

In Fig. 7 a slightly modified form of the invention is illustrated. In place of applying the vacuum head 32 directly to the arm of the hand lever, which contains the handle, the vacuum head 32 is applied to an arm 11^a of the lever. The arm 11^a may be placed on the side of the press body 10 opposite the one on which the handle portion 11^b is placed. The two arms 11^a, 11^b of the hand lever are rigidly connected by a cross connection in the form of a shaft 12^c secured in the lever arms 11^a, 11^b and extending through the press body and rotatively mounted therein.

It will be understood that wherever the expressions "hand lever" occurs in the claims it is intended to include a hand lever of the first or second order and one in which the vacuum head may be applied to any arm thereof.

While the invention has been shown and described in connection with a vacuum head, it is obvious that other means may be em-

ployed for supporting the hand lever in raised or starting position and that pneumatic means, either in form of pressure or vacuum may be employed for releasing the hand lever from such position.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. Automatic die press stopping mechanism, comprising in combination, the hand lever of the press starting and stopping mechanism of a press, a vacuum head having a suction end arranged to contact with said hand lever, whereby the lever is supported in starting position when vacuum is created at the suction end of said vacuum head, said vacuum head being connected with a vacuum source, a vent tube leading from the suction end of said vacuum head and having an air valve thereon, and a valve actuating member operated by a malfunctioning of a part of the press.
2. Automatic die press stopping mechanism, comprising in combination, the hand lever of the press starting and stopping mechanism of a press having a strip feed way and finger bar actuating mechanism, a vacuum head having a suction end arranged in contact with said hand lever, whereby the lever is supported in starting position when vacuum is created at the suction end of said vacuum head, said vacuum head being connected with a vacuum source, a vent tube leading from the suction end of said vacuum head and having a plurality of air valves thereon, and capable of being opened by automatically operated valve actuating members, one of said members being controlled by the strips in the feed way, and the other by the finger bar actuating mechanism.
3. Automatic die press stopping mechanism, comprising in combination, the hand lever of the press starting and stopping mechanism of a press having a strip feed way and connectible and disconnectible finger bar actuating mechanism, a vacuum head having a suction end arranged to contact with said hand lever, whereby the lever is supported in starting position when vacuum is created at the suction end of said vacuum head, said vacuum head being connected with a vacuum source, a vent tube leading from the suction end of said vacuum head, an air valve on said vent tube and mounted on one member of said connectible and disconnectible finger bar actuating mechanism, and a valve actuating trigger, which is held in an inactive position by the other member

of the finger bar actuating mechanism when said members remain connected.

4. Automatic die press stopping mechanism, comprising in combination, the hand lever of the press starting and stopping mechanism of a press having a strip feed way and a connectible and disconnectible finger bar actuating mechanism, a vacuum head having a suction end arranged to contact with said hand lever, whereby the lever is supported in starting position when vacuum is created at the suction end of said vacuum head, said vacuum head being connected with a vacuum source, a vent tube leading from the suction end of said vacuum head, an air valve on said vent tube and mounted on one member of said connectible and disconnectible finger bar actuating mechanism, and a spring actuated, valve operating trigger mounted on said member of the finger bar actuating mechanism and having a finger normally engaging with the other member of the finger bar actuating mechanism, and operating, when the two members of said finger bar actuating mechanism are disconnected, to open said air valve.

5. In automatic die press stopping mechanism, the combination of a hand lever supporting vacuum head, a vent tube therefor, and an air valve on said vent tube, a connectible and disconnectible finger bar actuating mechanism, said air valve being mounted on one member of said finger bar actuating mechanism, and a valve actuating trigger, normally held in inactive position by the other member of said finger bar actuating mechanism when the two members thereof remain connected.

6. In automatic die press stopping mechanism, the combination of a hand lever supporting vacuum head, a vent tube therefor, and an air valve on said vent tube, a connectible and disconnectible finger bar actuating mechanism, said air valve being mounted on one member of said finger bar actuating mechanism, and a valve actuating trigger having a finger which is engaged by the other member of said finger bar actuating mechanism, whereby the valve operating trigger is held in an inactive position when the two members of the finger bar actuating mechanism remain connected.

7. Automatic die press stopping mechanism, comprising in combination, the hand lever of the press starting and stopping mechanism of a press having a strip feed way, a vacuum head having a suction end arranged to contact with said hand lever, whereby its lever is supported in starting position when vacuum is created at the suction end of said vacuum head, a vacuum pipe leading from said vacuum head to a vacuum source, a valve in said head for controlling the passage therein to the vacuum tube, said

valve having a stem arranged to be engaged by the hand lever whereby said passage is opened when the hand lever is in contact with the suction end of the vacuum head, a 5 vent tube leading from the suction end of the vacuum head and having an air valve thereon, a normally inactive trip device associated with the strip feed way of the press, and having a valve actuating member operating 10 to open said valve when an abnormal condition arises in the strip feed way.

8. Automatic die press stopping mechanism, comprising in combination, the hand lever of the press starting and stopping 15 mechanism of a press having a strip feed way, and finger bar actuating mechanism, a vacuum head having a suction end arranged to contact with said hand lever, whereby the lever is supported in starting position when 20 vacuum is created at the suction end of said vacuum head, a vacuum pipe leading from said vacuum head to a vacuum source, a valve in said head for controlling the passage therein to the vacuum tube, said valve 25 having a stem arranged to be engaged by the hand lever whereby said passage is opened when the hand lever is in contact with the suction end of the vacuum head, a vent tube leading from the suction end of 30 the vacuum head and having air valves thereon, automatically operated by valve actuating members, one of said members being controlled by the strips in the feed way, and the other by the finger bar actuating mechanism.

9. Automatic die press stopping mechanism, comprising in combination, the hand lever of the press starting and stopping mechanism of a press having a strip feed 40 way and connectible and disconnectible finger bar actuating mechanism, a vacuum head having a suction end arranged to contact with said hand lever, whereby the lever is supported in starting position when vacuum 45 is created at the suction end of said vacuum

head, a vacuum pipe leading from said vacuum head to a vacuum source, a valve in said head for controlling the passage therein to the vacuum tube, said valve having a stem arranged to be engaged by the hand lever whereby said passage is opened when the hand lever is in contact with the suction end of the vacuum head, a vent tube leading from the suction end of the vacuum head and having an air valve thereon, mounted on one of the members of said finger bar actuating mechanism, and a valve operating trigger engaged by the other member of said finger bar actuating mechanism, when both members thereof remain connected, whereby 55 said trigger is normally held in an inactive position.

10. Automatic die press stopping mechanism comprising in combination, the hand lever of the press starting and stopping 60 mechanism of a press, means engaging and supporting said hand lever when in raised position, an air tube leading from said means and having an air valve thereon and an automatically operated valve actuating member. 65

11. Automatic die press stopping mechanism comprising in combination, the hand lever of the press starting and stopping mechanism of an automatic die press, a vacuum head having a suction end arranged to contact with an arm of said hand lever whereby the lever is supported in starting position when vacuum is created at the suction end of said vacuum head, said vacuum 70 head being connected with a vacuum source, a vent tube leading from the suction end of said vacuum head and having air valves thereon distributed among a plurality of locations among the press, said air valves being openable by a malfunctioning of the press parts at such locations, to vent the suction head and release the hand lever therefrom. 75

CHARLES D. McDONALD.
